(57) CLAIM

The ornamental design for a string bed design for a tennis racquet, as shown and described.

DESCRIPTION

FIG. 1 is a front view showing our design, the undisclosed opposite side being a mirror image; and, FIG. 2 is a perspective view thereof.

The broken line showing is included for the purpose of illustrating and forms no part of the claimed design.

1 Claim, 2 Drawing Sheets

FIG. 1

FIG. 2
